Primary Examiner — Susan Bennett Hattan*Assistant Examiner* — Omeed Agilee(74) *Attorney, Agent, or Firm* — Stoel Rives LLP(57) **CLAIM**

The ornamental design for a medical device dispenser, as shown and described.

DESCRIPTION

FIG. 1 is a first perspective view of a medical device dispenser.

FIG. 2 is a second perspective view thereof.

FIG. 3 is a front view thereof.

FIG. 4 is a back view thereof.

FIG. 5 is a right side view thereof.

FIG. 6 is a left side view thereof.

FIG. 7 is a top view thereof; and,

FIG. 8 is a bottom view thereof.

The broken lines in the drawings depict portions of the medical device dispenser that form no part of the claimed design.
